(57) **CLAIM**

The ornamental design for a window opener as shown and described.

DESCRIPTION

FIG. 1 is a perspective view of a window opener showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is second perspective showing the window opener. The broken lines in the drawings illustrate portions of the window opener that form no part of the claimed design. The article is shown with a symbolic break in its length. The appearance of any portion of the article between the break lines forms no part of the claimed design.

1 Claim, 8 Drawing Sheets
